UNITED STATES PATENT OFFICE.

JAMES FRANCIS BUCKLEY, OF DARTFORD, ENGLAND, ASSIGNOR TO ALLEN AND HANBURY'S, LIMITED, OF LONDON, ENGLAND.

GRINDING-MACHINE.

SPECIFICATION forming part of Letters Patent No. 769,207, dated September 6, 1904.

Application filed April 18, 1903. Serial No. 153,191. (No model.)

To all whom it may concern:

Be it known that I, JAMES FRANCIS BUCKLEY, a subject of the King of Great Britain, and a resident of 27 Highfield road, Dartford, in the county of Kent, England, have invented certain new and useful Improvements in Grinding-Machines, of which the following is a specification.

The main object of the present invention is to provide simple and efficient means for grinding and polishing the concave faces of punches used in compressing-machines for making medicinal tablets.

In the accompanying drawings I have shown a machine embodying my invention.

Figure 1 is a side elevation. Fig. 2 is a plan view of the machine complete; and Fig. 3 is a sectional elevation, on an enlarged scale, of the upper or working part of the machine only.

The machine which I have chosen to illustrate my invention is a power-driven machine comprising a framing *a*, supporting in suitable bearings a driving-shaft *b*, carrying fast and loose pulleys *d* and *e* and two grooved pulleys *f* and *g* for driving the machine, the former of which is much larger than the latter. The machine proper is mounted on a bed-plate *h*, supported on the framing *a*. Upon the bed-plate *h* is a head-stock *i*, and within the head-stock is a sleeve *j*, carrying a grooved pulley *k*. Rotation may be imparted to the pulley *k* and sleeve *j* by means of the band *l*, running over the pulley *g* on the shaft *b*.

Within the sleeve *j* is a spindle *m*, which is free to slide endwise in the sleeve, but must rotate therewith by reason of the keyway *n* (see Fig. 3) and a corresponding key in the sleeve to engage therewith. One end of the spindle *m* carries a chuck *o* of any suitable kind for holding the punch *p* or other tool to be ground. The other end of the spindle *m* is reduced in diameter and is embraced by a snugly-fitting collar *q*, which lies comfortably between the shoulder *r* and the nut *s*, so as not to impede the rotation of the spindle. The endwise movement of the spindle *m* in the sleeve *j* to advance the punch up to the grinding-surface is effected by the collar *q*,

which is preferably controlled by a lever *t*, 50 fulcrumed at *u* and having a pivotal connection with the collar *q*, as shown in Fig. 3.

v is an adjustable stop for the lever *t*, by means of which the endwise movement of the spindle *m* and the punch *p* in a forward direction is limited to any desired extent.

w is the grinding-wheel or other device used for grinding or polishing the punch. This wheel is attached firmly to its spindle *x*, which is mounted in suitable bearings in the head-stock *y*. The spindle *x* receives its motion by a band *z*, passing over driving-pulley *l*, attached to the spindle *x*, and the large driving-pulley *f* on the driving-shaft *b*, before mentioned, these pulleys being placed in the same vertical plane. The pulley *k* of the punch-carrying spindle being arranged at right angles to that on the driving-shaft of the machine, the band connecting them has to be twisted.

The cutter or polishing device may be an ordinary emery-wheel, or it may be a soft-steel ball charged with diamond-dust, the latter being preferable for grinding deep-sunk punches.

The machine may, if desired, be employed for other forms of internal grinding by changing the position of the grinding-head with regard to the sliding spindle.

In operating the machine the punch or other article to be ground having been fitted to the supporting-spindle, the latter is advanced against the grinding-wheel. This wheel, as will be understood from the foregoing description, is rotated at a fast rate of speed, while 85 the article being ground is turned more slowly, owing to the smaller size of the pulley on the driving-shaft. The advance of the punch is continued by means of the hand-lever *t* until the latter is arrested in its movement by the stop *v*, previously adjusted to the proper extent. In this way a number of punches may be ground, so as to be identical in every respect.

It may be remarked that this machine will suffice to grind or repair the damaged faces of 95 the punches without necessitating the softening of the latter. It is the usual custom at present when repairs are required to soften

the punches and turn them out in a lathe, after which they are retempered. The softening of the punches is generally effected by heating them, which not only occupies time, 5 but also when constantly done renders them liable to deteriorate as regards the quality of the steel, and hence the advantage of a device which obviates the softening altogether.

The driving-shaft is preferably placed below the bed, so as to avoid the employment of overhead shafting.

What I claim as my invention, and desire to secure by Letters Patent, is—

In a machine for grinding punches, the combination of a framing and a bed-plate thereon, 15 a chuck-carrying spindle and a grinding-spindle arranged at an angle to each other above said bed-plate, a bearing on the bed-plate for the grinding-spindle, a sleeve surrounding the

chuck-carrying spindle and fitted to said spindle to turn with it but in which said spindle is movable lengthwise, a bearing on the bed-plate in which the sleeve rotates but is confined lengthwise, a driving-shaft and stationary bearings therefor on said framing below the bed-plate, a pulley on said grinding-spindle and one on said sleeve, two pulleys on said driving-shaft, and two belts between the latter pulleys and the two spindle-pulleys for giving rotary motion to the two spindles. 20 25 30

In testimony whereof I have signed my name to this specification in the presence of two subscribing witnesses.

JAMES FRANCIS BUCKLEY.
